UNITED STATES PATENT OFFICE.

DOUGLAS TURNER, OF ST. LOUIS, MISSOURI, ASSIGNOR TO THE MEASUREGRAPH COMPANY, OF ST. LOUIS, MISSOURI, A CORPORATION OF MISSOURI.

RIBBON MEASURING, COST COMPUTING, AND WINDING MACHINE.

Application filed December 8, 1919. Serial No. 343,335.

This invention relates to improvements in ribbon measuring, cost computing and winding machines of the general type illustrated in the patent to Hosch, No. 1,242,192, dated 5 October 9, 1917, and on which the present invention is an improvement.

One of the objects of the present invention is to provide for a novel construction and arrangement of parts whereby I am enabled to provide a machine more compact 10 in structure and of less height than the machine of the patent referred to; another object of the invention relates to the location of the presser roll and the provision of 15 a clear glass window thereover to enable the operator to note the behavior of the material while being measured; another object of the invention relates to an improved gripping device for the ribbon, which is combined with the presser roll in such manner 20 as to raise the latter simultaneously with the lowering of the gripping device; another object of the invention consists in providing the gripping device with a plurality of gripping fingers which are independent in their 25 operation, thereby insuring an even grip on the fabric while the latter is being cut; another object of the invention relates to an improvement in the reel construction for the 30 knife, whereby lint and dirt are prevented from going into the reel; another object of the invention relates to an improvement in the knife slot, which is open at the forward end and so arranged that dirt and lint can 35 be easily blown out of this slot by the operator; another object of the invention relates to an improved winding drum mounted on ball bearings and so constructed and arranged that oil will not leak out of said bearings and soil the ribbon being measured, and 40 dirt and lint cannot work into the bearings; a further object of the invention relates to the novel arrangement of finger pads below the surface of slots designed to receive the 45 lower edges of the hold-down fingers, whereby to insure a better grip on the goods while being cut; and, finally a further object relates to an improvement in the mounting of the take-up reel for the knife whereby the 50 latter may be easily removed for the purpose of cleaning.

In addition to the above-specified objects of the invention, further objects relate to

details of construction, and to combinations and arrangements of parts, whereby the objects recited are attained and a machine compact and durable in structure, simple and reliable in operation, and convenient and accessible for use is provided. Such additional objects of the invention, with their attendant advantages, will be set forth in the course of the detailed description of the invention to follow.

The invention is illustrated in the accompanying drawings in which:

Figure 1 is a plan view of the complete machine, the winding drum being partly broken away to better illustrate the construction;

Figure 2 is a rear elevation;

Figure 3 is a section on the line 3—3 of Figure 1;

Figure 4 is a view in front elevation of the takeup reel and hold-down finger block; said parts being indicated by full and dotted lines, respectively, at the right of the center of Figure 1.

Figure 5 is a view in right side elevation of the parts illustrated in Figure 4;

Figure 6 is a transverse sectional view 80 through the take-up reel of Fig. 4 showing the spiral spring for operating the same;

Figure 7 is a sectional view taken on the line 7—7 of Figure 6;

Figure 8 is a cross sectional view through 85 the knife slot taken on the line 8—8 of Figures 1 and 9;

Figure 9 is a longitudinal sectional view taken on the line 9—9 of Figure 1 and viewed in the direction of the arrows;

Figure 10 is a vertical sectional view 90 through the knife frame, taken on the line 10—10 of Figure 5;

Figure 11 is a section through the cost indicating charts, taken on the line 11—11 95 of Figure 1;

Figure 12 is a broken sectional view illustrating the construction at one end of the cost indicating charts and taken on the line 12—12 of Figures 1 and 11;

Figure 13 is a partial plan view of the length indicating mechanism and presser roller, the cases being removed, the same being substantially a sectional view on the line 13—13 of Figure 17;

Figure 14 is a view in side elevation of the

resilient zero stop mechanism shown in Figure 13;

Figure 14^a is a sectional view on the line *w—w* of Figure 14;

5 Figure 15 is a sectional view illustrating the length indicating mechanism and presser roller construction, taken on the line 15—15 of Figure 1;

10 Figure 16 is a detail view illustrating the throw-out clutch mechanism;

Figure 17 is a section on the line 17—17 of Figure 13, illustrating certain features of the length indicating mechanism; and

15 Figure 18 is a fragmentary view of the brake device shown in Figure 17 for preventing movement of the measuring roller after the presser roller has been raised.

The machine as a whole is mounted on a base 1, Figures 1, 2 and 15, which is provided on the left side, as viewed in Figure 1, with a pocket 2 to receive the roll of ribbon to be measured. At its inner end, or that toward the operator, the frame 1 provides a casing head 3 and mounted in this 25 casing head at the right of the machine, in a manner to be presently described is a winding drum 4. This winding drum is of the general construction described and claimed in the patent to Hosch, No. 1,253, 30 243, dated January 15, 1918. In the present case the winding drum as a whole is mounted on a bronze casting 5 Fig. 2 which is secured in a recess in the casing head 3 by means of screws 6. The spindle 7 of the 35 reel or drum has mounted on its inner end a pinion 8 which meshes with a gear wheel 9 on the stub shaft 10 which latter is provided on its inner end with a crank handle 11 for turning the drum. The spindle 7 and stub shaft 10 are mounted to rotate in ball bearings 12 as shown. The spindle 7 is provided 40 on its outer end with a cylindrical head 13 Fig. 1 at the base and around the periphery of which are secured the resilient fingers of the winding drum 4. The casing head 3 is 45 provided with a circular recess 14 for receiving the inner end of the winding drum and head 13, the object of this being to prevent the ribbon from winding up onto the non-resilient back portion of the winding drum, which would make it more difficult to remove the roll of ribbon from the drum, as the ribbon is wound thereon with considerable tension. The major portion of the head 50 13 is of less diameter than the interior of the winding drum, as shown in Figure 1, so as to permit of the fingers being bent inward as the ribbon is wound on the drum, and the forward or outer end of said head 55 13 is beveled as indicated at 15 to permit the end of the ribbon to be inserted between the slots of the fingers of the winding drum and moved backward thereon without engaging the end of the head 13.

60 65 The length and price indicating mecha-

nisms, hereinafter described, are mounted on a common base plate 16, Figures 13, 15 and 17, which is adapted to be supported by shelves 17. Figure 15, formed on the interior of the casting of the base 1, and within an upright portion 18 of said base extending longitudinally thereof, Figures 1 and 11, and constituting a housing for receiving the length and price indicating mechanisms which are respectively located upon the opposite ends of said plate. When so positioned the base plate 16 and the mechanisms carried thereby are adapted to be locked in place by a lock 19, shown in Figures 2 and 15.

The base plate 16 is made substantially circular at its inner end, as indicated at 20, Figure 13, and mounted on this circular portion of the plate, as shown also in Figures 15 and 17, is the length indicating mechanism to be later described, which is adapted to be actuated by the passage of the ribbon over a measuring roller 21, Figures 11 and 15, the ribbon while being measured being held in frictional engagement with the measuring roller by means of a presser roller 22. Extending upward from the base plate 16 at the point of juncture of the circular portion 20 with the body of the base plate 16 is a frame plate 23, Figures 13 and 15. Mounted in a bearing 24 Fig. 15 secured on the outer side of said frame plate is the spindle 25 of the measuring roller 21, said measuring roller being wholly supported at one end only by means of this spindle and bearing. Mounted on the spindle 25 on the inner side of the frame plate 23 is a cam wheel 26 Fig. 17 having a shoulder 27 and beyond this cam wheel is a pinion 28 which meshes with a gear wheel 29. The gear 29 is fast on a shaft 30, see Figures 13, 16 and 17, which is supported at one end in the frame plate 23 and at its other end in a bracket 31 mounted on the base plate 16. Slidably mounted on the shaft 30 is a sleeve 32 carrying at one end a male cone clutch 33 which engages in the gear 29. Between a collar 34 on the shaft 30 and the end of the sleeve 32, is mounted a coil spring 35 which normally bears against the sleeve 32 and forces the clutch member 33 into engagement with the gear 29. The sleeve 32 is provided with an annular recess 36 which receives the bifurcated end of a vertical arm 37 carried by one end of a slide plate 38 which at its other end is provided with a second vertical arm 39 notched in its upper end to loosely receive the end of a lever 40 which is pivoted intermediate its ends on a post 41 and the outer end 42 of which lever is loosely received into a notch 43 (Figure 15) of a push bar 44 slidably mounted in the upper end of a bracket plate 45 mounted on the circular portion 20 of the base plate; the said push bar having a thumb piece 46 project-

ing through an opening 47 in the rear wall of a case 48 inclosing the length indicating mechanism. The inner end of the push bar 44 is slotted, as indicated at 48^a, to receive 5 a pin 49 secured in a standard 50 mounted on the circular portion 20 of the base plate, whereby the inner end of the push bar is 10 slidably supported by said pin. The bracket plate 45 is provided on its rear side with a stop 51 which engages the inner side of the thumb piece 46 to limit the inward movement of the push bar 44. When this push bar is 15 pressed inward the lever 40 Figs. 13 and 16, will be turned to move the slide plate 38 outward and thereby move the sleeve 32 against the resistance of the spring 35 to release the clutch 33 from engagement with the gear wheel 29. The purpose of this construction will presently be described.

20 Mounted on the sleeve 32 is a pinion 52 which meshes with a large gear wheel 53 Fig. 13, which is mounted on a sleeve 54 rotatably mounted on a shaft 55 mounted at one end in the frame plate 23 and at the other 25 end in the standard 50 Fig. 15. Secured on the inner end of the sleeve 54 is a gear wheel 56 which meshes with a similar gear wheel 57 Fig. 17, mounted on the end of a shaft 58. This shaft drives the price indicating mechanism, which will now be described.

The shaft 58 extends along the base plate 16 to the forward part of said base plate containing the price indicating charts illustrated in Figures 1, 11 and 12, where it is 35 provided with a pinion 59 meshing with a gear 60 on the shaft 61 of a winding cylinder 62. The gear 60 meshes with an idle gear 63 which in turn meshes with a gear 64 on the shaft 65 of a second winding cylinder 66. The ends of a chart 67 doubled upon 40 itself, and containing columns of figures to indicate prices per yard of the material to be measured are secured to the respective 45 rollers 62 and 66 and the doubled portion of said chart is wound about a chart-return-cylinder 68 which is loosely mounted on a fixed shaft 69 supported at opposite ends in brackets 70 secured on the under side of the 50 base plate 16 and provided on its interior with a coil spring 71, one end of which is secured to the cylinder 68 and the other to the fixed shaft 69. The length-indicating mechanism is driven from the gear 53 Figs. 55 13 and 15, as now to be described.

The numeral 72, Figure 15, indicates a sleeve which is fast with the gear 53 and rotatably mounted on the shaft 55, said sleeve carrying a bevel gear 73 which meshes 60 with a bevel gear 74 which is on the lower end of an arbor 75 and carrying what may be termed the inch hand 76 of the length indicating dial 77. Slidably mounted on the arbor 75 is a sleeve 78 carrying a pinion 65 79, Fig. 13, which meshes with a gear 80

mounted on a stub shaft on a bracket 81, Figures 13 and 15, and having fixed thereon a pinion 82 which meshes with a gear 83 which is mounted on the lower end of a sleeve 84 which sleeve extends through the 70 dial plate 85 (Figure 15) and carries what may be termed the yard hand 86. Referring to Figure 1, the dial 77 is provided with a circular series of numbers indicating 75 inches, and a circular series of fractions, indicating fractions of a yard, said numbers and fractions being adapted to be read in connection with the inch hand or pointer 76, and another circular series of numbers running from zero to 11 indicating yards, and 80 which are adapted to be read in connection with the yard hand or pointer 86. Through the gearing above described the hand 76 travels 12 times as fast as the hand 86 and in reading the dial the hand 86 will indicate 85 the number of yards measured and the hand 76 the number of inches, or the fraction of a yard over the number of yards indicated by the hand 86. In measuring goods, and particularly ribbon, as the ribbon is passed 90 over the measuring roller 21 the latter is rotated and through the gearing described the hands 76 and 86 are rotated over the dial and simultaneously through the medium of the shaft 58 the winding cylinders 62 and 95 66 will be rotated to wind the chart 67 thereon from the chart return cylinder 68 against the resistance of the coil spring 71. At the end of the measuring operation the 100 relation of the gearing and the disposition 105 of the numbers on the charts is such that they will indicate opposite fixed columns of numbers indicating prices per yard, the cost of the material measured at any given price. This feature of the invention is common to 108 the type of machine to which my invention relates and is well understood by those skilled in the art and need not be particularly described. It may be briefly stated, however, that in Figure 1, the numerals 87 and 88 110 indicate, respectively, the fixed column of figures indicating prices per yard, and the numerals 89 and 90 the respective columns of figures exhibited by the chart 67. These 115 numbers appear through two slots 91^a and 92^a in a face plate 93^a extending over the winding cylinders 62 and 66, and which face plate is in turn covered by a clear glass plate 94^a (Figure 11). As shown in Figure 1, the figures in the columns 89 and 90 indicate the cost of two yards of material, the measured portion shown at the dial, at any 120 price per yard, from \$0.05 to \$1.25, shown in columns 87 and 88.

125 After a length of material has been measured the next operation of the machine consists in severing the measured portion from the bolt of ribbon. This is effected by manipulating first the ribbon gripping or hold-down mechanism and then the cutting mecha-

nism, which devices will be described in their order.

Referring particularly to Figures 2 to 7 the numeral 91 indicates a rock shaft which is pivotally mounted at one end in a bracket 92, secured on the inner side of the casing head 3, and at its other end in a block 92^c which is secured edgewise in the casing head 3 to the right of a central circular portion 92^b of said casing head. (Figures 1, 2 and 15), which supports the circular portion 20 of the base plate 16. The shaft 91 has secured on its outer or left hand end a crank 93, Figs. 2 and 3. Pivotally connected at its lower end to the outer end of this crank is a bent arm 94 which is pivotally secured at its upper end to a stem 95 provided at its upper end as indicated at 94', Figure 3, with a knob 96 for depressing it. The stem 95 is slidably mounted in a sleeve bearing 97 secured in the top of the casing head 3, and depression of said stem to rock the shaft 91 is effected against the resistance of a coil spring 98 secured at its lower end to the arm 94 and at its upper end to the top of the casing head 3. Secured on the other end of shaft 91 on either side of the block 92^c Figs. 1, 4 and 9 are cranks 100 carrying pins 101 to which are connected the lower ends of coil springs 102. The upper ends of springs 102 are connected to pins 103 which are secured on the outer sides of corresponding arms 104 pivotally mounted at their inner ends, (Figures 5 and 9) on a pin 105 mounted in the upper end of the block 92^c. The numerals 106 indicate corresponding links which connect the pins 101 and 103 and hold the same a given distance apart. These links have slotted connections at their ends with the pins 101 and 103, as indicated at 107, to allow of a slight longitudinal movement of the links independently of the pins. The springs 102 hold the arms 104 and the cranks 100 together as spaced by the links, or radius rods 106. Pivotally mounted at 108, (Figure 9) at the outer end of each of the arms 104 is a hold-down finger 109, having a serrated bottom edge, as indicated at 110. The hold-down fingers 109 are pivoted substantially centrally of their length and at their rear ends are connected by means of small coil springs 111, Figures 5 and 9, to lugs 112 provided on the lower side of the arms 104. On the inner side of each of these arms is a pin 113 which enters a slot 114 provided in the rear end of the hold-down fingers, whereby to permit of an independent movement of the hold-down fingers 109 about the pivot 108 and at the same time limit the downward movement of the rear ends of said hold-down fingers under the influence of the spring 111. The hold-down fingers 109 operate in conjunction with recesses formed in the slotted runway for the knife of the machine as

illustrated particularly in Figures 1 and 8. Referring to these figures, the numerals 115 indicate two parallel bars which are secured in assembled relation on a milled shoulder 116, extending longitudinally of the base of the machine, by means of screws 117. On the upper side of each of these bars is provided a longitudinal recess 118, extending approximately half-way of the length of said bars from the inner ends thereof, and mounted in these recesses are leather pads 119 the upper surface of each of which is below the top elevation of the recesses. These recesses are immediately below and in line with the hold-down fingers 109 and when the latter are depressed by pushing down on the knob 96 their serrated edges enter the said recesses and in this way the gripping of the material is greatly facilitated as the latter will be depressed into the recesses by the hold-down fingers, which will thus be given a firmer grip on the ribbon while at the same time pressing it into engagement with the leather pads. Referring particularly to Figure 9, each of the bars 115 at its inner end is cut away to provide a recess 120 for receiving the rear end portion of the hold-down fingers 109 to which the spring 111 is connected. Such end portion of each hold-down finger is in the form of a depending lug 121, (see also Figure 5), the outer face of which extends parallel with the bottom of the recess 120. The bottom edge of each hold-down finger extends at substantially a right angle to the outer edge portion of the lug 121 so that when the arms 104 are turned downward by depressing the knob 96 the bottom edge of each hold-down finger adjacent to the lug 121 will engage the upper edge of the bar 115 at the corner, indicated by 122, formed by the recess 120, which corner acts as a pivot forcing the rear ends of the hold down fingers to rise as the forward portions are carried downward by the pivot 108. In this movement the slots 114 will rise over the pins 113 against the tension of the springs 111. In the initial operation, when the shaft 91 is turned by depressing the knob 96, the arms 104 will be turned downward by the tension exerted by the springs 102. If, for any reason, such as inequality of the thickness of the material, a fold in the latter, or the like, one of the hold-down fingers is prevented from being depressed the full distance into the slot 118, such obstruction will not interfere with the movement of the other hold-down finger, as the pin 101 on the corresponding crank 100 will move down in the slot 107 at the bottom of the link 106 and the slot 107 at the top of said link will slide over the pin 103 of the arm 104, such additional movement thus provided permitting the corresponding finger 109 to be fully depressed. 130

The independent movement between the hold-down fingers thus provided is sufficient in extent to more than compensate for any obstruction which would ordinarily in practice be presented to the movement of either finger. When the said fingers are fully depressed the material will be pressed into the recesses 118 and frictionally held between the leather pads 119 and the serrated edges 110 and thus be prevented from movement in the cutting operation. From the construction of the hold-down mechanism described it will be seen that I provide a gripping device which is flexible and resilient throughout; and should any variations in the height of the small leather pads 119 occur, or, through other cause, should the elevation of the material being measured on either side of the knife slot, hereinafter referred to, be different, the hold-down device will compensate for such difference and will exert an even pressure so as to insure the proper operation of the knife. This latter operation is effected by the mechanism now to be described.

The block 92^c previously referred to is located immediately back of the ends of the bars 115 and is cut away on its inner side at the top to provide a recess 123, (Figure 5) for receiving the ends of said bars. These bars are maintained in parallel spaced relation at their upper sides to provide a knife slot 124 and below the slot 124 the separation between the bars is increased 35 to provide a longitudinal opening 125 Fig. 8 which extends throughout the length of the bars and through the end 126 of the housing 18 which end is slotted as indicated at 127 (Figure 1) to form a continuation of the slot 124. The provision of the opening 125, Figure 8, extending through the front end of the machine is quite important as it permits the operator to blow through said opening and along the slot 124 and thus remove 45 any lint or threads which might have accumulated in the latter. Referring to Figure 4, the numeral 128 indicates a plate which is pivotally mounted at its upper end on the pin 105 previously referred to, located at the upper end of the block 92^c, and at its lower end the plate 128 has rotatably mounted on a bearing screw 129 a knife reel 130 within which is mounted a coil spring 131, one end of which is connected to the reel and the other to a fixed bearing on the plate. Rotatably mounted on the pin 105 between the plate 128 and the block 92^c is a sheave 132. A wire 133 is secured at one end to the reel 130 and wound about the same and passing over the sheave 132 is secured at its outer end to a slide bar 134, the connection being indicated by the numeral 135 in Figure 5. Before being connected to the bar 134 the end of the wire is lead through a small hole 136 provided in a flange 137 of the block 92^c. The hole 136 is a few thousandths of an inch larger than the wire, and its purpose is to prevent threads and lint from being drawn from the opening 125 back into the mechanism of the knife reel. The block 70 92^c is recessed on its side, as indicated by the numeral 138 in Figures 4 and 5 to accommodate the sheave 132 and the reel 130. The block 92^c is located in a recess provided in the casing head 3 adjacent to the right hand side of the circular portion 92^b, as viewed in Figures 1 and 2, and this recess is normally closed by a plate 139 (Figure 9) which is pivotally mounted at its lower end in the front wall of the casing head 3 75 by means of a pin and slot connection, as indicated at 140. The upper end of this plate is provided with an inwardly directed flange 141 which, when the plate is in position projects over the upper end of the block 92^c. On the under side of the flange 141 is located a lug 142, Figure 9, which is adapted to engage in a recess 143 (Fig. 5) provided in the top of the block 92^c. On the top of the flange 141 is a lug 144, (Figures 1 and 9) which acts as a stop to receive the impact of the cutter on its return movement, as hereinafter described, and has an integral portion 145 projecting outward beyond the plate 139 and acting as a handle. Normally, the plate 139 is held in its closed position by means of a screw 146 passing through the lug 144 and into the top of the block 92^c. Near the bottom of the plate 139 is pivotally mounted a link 147 which is 90 provided on its upper side with a slot 148 for receiving a pin 149 on the side of the plate 128 (Figures 4, 5, and 9). When it is desired to gain access to the reel 130 to clean or repair the same, the screw 146 is 95 removed and by grasping the handle 145 the plate 139 is lifted to raise the lug 142 out of the recess 143 when the plate 139 may be swung outward on the pivotal connection 140 as a hinge. In this movement the link 110 147 will cause the plate 128 carrying the reel 130 to be swung outward on the pin 105 as a pivot, when the reel may be readily inspected for any purpose and if necessary removed from the plate 128 by unscrewing 115 the screw 129. The slide bar 134, Figure 5, supports a housing 150 in which is mounted a knife blade 151, the bar 134, and knife blade 151 being held in the housing 150 by a screw 152. The housing 150 presents a flat surface, or edge 153 on either side of the bar 134 and blade 151, which is adapted to slide on the upper side of the bars 115. The cutting edge of the knife extends at an angle across the space 154 between the bar 134 and the flat side 153 of the housing, so as to give a shearing cut to the fabric passing into the space 154 Figure 5 as the housing 150 is moved forward. In assembling the parts the bar 134 120 125 130

and the blade 151 project downward through the slot 124 in the upper side of the runway shown in Figure 8, being inserted therein through the slot 127 at the forward end 5 of the machine, (Figure 1), and after being inserted a screw 155 is placed in the shoulder 116 to extend across the opening 125 to prevent the cutter from being pushed out of the slot in its forward movement. Pins 10 156 project from opposite sides of the bar 134 at the front and rear thereof, which work in the opening 125 and prevent the bar 134 and cutter 151 from being lifted out through the slot 124 by engaging on 15 the shoulders formed at either side of said slot by the opening 125. Preferably the housing 150 is milled as indicated at 157 in Figure 4 to afford an engaging surface for the thumb in operating the cutter.

20 As will be seen from Figures 11 and 15, the upper presser roller 22 is covered by a casing member 158 which is secured to the frame plate 23 at one end by means of screws 159 and which projects outwardly for 25 some distance over a cover plate 160, which extends above and parallel with the face plate 93^a previously referred to, from the frame plate to the end of the machine, as shown by Figure 1. The cover plate 160 has 30 an opening in which is inserted the clear glass plate 94^a over the winding cylinders, as shown in Figures 1, 11 and 12, and is supported at its inner end on shelves 161 secured to the inner side of the frame plate 35 23, as shown in Figure 15, and at its other end in parallel frame plates 162 and 163 shown by dotted lines in Figure 1 and in full lines, as to the frame plate 163, in Figures 11 and 12. The frame plates 162 40 and 163 afford bearings for the shafts 61 and 65 of the winding cylinders 62 and 66 previously referred to. As shown by Figures 11, 13 and 15, the measuring roller 21 has its upper portion projecting a slight distance 45 above the upper surface of the cover plate 160, through an opening 164 in said cover plate, and the presser roller 22 likewise projects a slight distance below the bottom of the casing 158, the space 165 between the 50 bottom of the casing 158 and the cover plate 160 being for the purpose of permitting the material to be measured to be inserted between the rollers 21 and 22. In the top of the casing 158 is a clear glass plate 166 which 55 permits ready observation of the behavior of the material being measured by the operator.

60 Before inserting the material between the rollers, however, it is necessary to first raise the roller 22 out of engagement with the roller 21. This operation is effected when the knob 96 is depressed to lower the gripper mechanism, by the construction now to be described, referring particularly to Figures 15 and 17.

65 Secured on the shaft 91 is a crank 167 pro-

vided on its outer end with an apertured lug 168 through which extends the lower end of a rod 169 having on its lower end a head 170 between which and the lug 168 is inserted a coil spring 171. Pivotaly mounted 70 at 172 on the frame plate 23 is a bell crank lever 173 one arm of which is pivotally connected to the upper end of the rod 169 and the other to a rod 174 the outer end of which is pivotally connected to the lower end of 75 a lever 175 which is secured on the end of a shaft 176 which projects through and has a bearing in the frame plate 23 at its inner end and at its opposite end is mounted in a bearing 177 shown in dotted lines in Figure 80 11, provided on the inner wall of the casing 158. Fixedly secured on the shaft 176 is a sleeve 178, Figure 13, extending throughout the length of the shaft and provided on its inner end adjacent to the frame plate 23 85 with a crank arm 179 to the outer end of which is secured a bearing shaft 180 on which the roller 22 is rotatably mounted. Secured on the sleeve 178 near opposite ends thereof are bent arms 181 to which are secured the lower ends of coil springs 182 the upper ends of which are secured in the top of the casing 158 as shown by dotted lines in Figures 15 and 17. These springs normally exert an upward tension and tend to 90 turn the crank arm 179 downward and thus hold the presser roller 22 in engagement with the measuring roller 21. It will readily be seen that as the crank arm 179 is turned 95 downwardly by rocking the shaft 91, the bell 100 crank 173 will cause the lever 175 to be moved to raise the outer end of the crank 179 and thus lift the presser roller 22 out of engagement with the measuring roller 21. The presser roller is adapted to be held in 105 its elevated position, and to be released to permit the springs 182 to lower it into engagement with the measuring roller, by the mechanism shown at the right of Figure 13. Mounted on the inner side of the casing 158 110 is a bracket 183 on which is pivotally mounted a bell crank 184 to one arm 185 of which is connected a coil spring 186 the other end of which is connected to the side wall of the casing 158. Pivotaly connected near the 115 outer end of the arm 185 is a push bar 187 provided with a button 188 on its outer end for operating it. The other arm of the bell crank lever is pivotally connected to one end of a latch 189 which is slidably supported in a projection of the bracket 183. The other end of the latch 189 is beveled on its upper side as indicated at 190. Projecting outwardly from the sleeve 178 is an arm 191. When the sleeve 178 is turned by the lever 175 to raise the presser roller 22 the end of the arm 191 bears against the inclined end 190 of the latch 189 and forces the latch outward against the resistance of the spring 186 until the end of the arm passes below the 130 120 125 130

latch, when the spring 186 operates to throw the latch inward and over the end of arm 191, which is the position shown in Figure 13. When it is desired to release the presser 5 roller the push button 188 is pressed inward, whereby to turn the bell crank 184 and withdraw the latch 189 out of contact with the arm 191, whereupon the springs 182 will operate to turn the sleeve 178 and move 10 the presser roller into engagement with the measuring roller.

Referring to Figure 13, it will be noted that the axes of the measuring roller and presser roller are inclined to the longitudinal axis of the machine. This inclined disposition of the rollers is resorted to for the purpose of compelling the winding drum to draw the ribbon through the machine in a straight line. In other words, the inclined 20 disposition of the rollers tends, at each revolution thereof, to draw or move the ribbon inward, or toward the frame plate 23. Thus the ribbon will be caused to travel uniformly in a straight line, with one edge in contact with the inner face of the plate 23, or at least such will be the tendency of the movement, so that the ribbon will be wound within the confines of a given space on the winding drum. But for this arrangement 25 the ribbon would be free to be wound irregularly on the winding drum, and as the winding advanced toward the outer end of the latter the tendency would be more and more to withdraw the ribbon from between 30 the presser and measuring rollers. This objection is entirely overcome by giving the slight incline to the rollers described.

I will now describe the mechanism for stopping the machine, to prevent injury to 40 the charts, when the full measuring capacity thereof, corresponding to twelve yards, has been utilized, in connection with the mechanism brought into play when the ribbon has been measured and cut and the machine 45 is to be returned to the zero position.

Secured on the shaft 75, Figure 13, is a disk 192 which is provided on its periphery with a shoulder 193. The gear 83 on sleeve 84, Figure 15, has on its upper side a pin 50 194 Fig. 13. The numeral 195 indicates a bracket which is mounted on the frame plate 23 and pivotally mounted in the outer end of this bracket is a post 196 (Figures 13 and 14) having secured on its upper end a dog 55 197 which in the zero position of the parts shown in Figure 13 is held against the pin 194 by a spring 198. Mounted on the post 196 beneath the bracket 195 is a plate 199 (Figure 14^a) which has pivotally mounted 60 at the outer end of a projecting arm a dog 200, one end of which is in the path of the shoulder 193 and the other end of which is connected by a spring 201 with a projection on the plate 199. The spring tends normally to pull the dog into engagement with 65 a pin 200^a on plate 199. Secured on the lower end of the post 196 is a contact arm 202, Figures 14 and 17, the inner end of which is connected by a coil spring 203 with a post 204 on the under side of the plate 199. Pivotaly mounted at 205 (Figure 17) on the frame plate 23 is a dog 206 which is normally held out of engagement with the shoulder 27 of the cam disk 26 by means of a coil spring 207 connected at one end to 70 said dog and at the other to the bracket 195. In starting the measuring operation, the pin 194 Figure 13, will first be moved away from the dog 197, which will thereupon be turned inward, or toward the operator by the spring 198, turning the post 196, and thereby the plate 199, to carry the dog 200 out of the path of the shoulder 193 on the disk 192. The turning of post 196 also moves the free end of the arm 202 into engagement with the dog 206, Figure 17, which acts as a stop to the movement of the parts in the direction described. These parts will remain in this position until the pin 194 has been carried through an entire cycle of 80 movement to a position to engage the opposite side of the dog 197 from that with which it is shown in engagement in Figure 13. Such engagement of the pin 194 with the rear side of said dog operates to further 85 rotate the post 196 and to move the plate 199 in the same direction as formerly, which places the spring 203 under tension and causes the free end of the contact arm 202 to press the dog 206 (Figure 17) inward, 90 so that the shoulder 27 on the disk 26 will engage the end of said dog and stop further movement of the measuring roller, this stoppage occurring when the limit of measurement, namely twelve yards, has been reached. 95 By this means, I prevent stretching, or tearing the chart 67 by accidentally continuing the movement of the measuring roller beyond the capacity of said chart.

After any given measuring operation the gripping mechanism 109 is depressed and the presser roller 22 simultaneously raised as heretofore described, the cutter is moved outward by hand to sever the length of material measured, the ribbon wound on the winding drum is removed, the cost thereof noted and the length indicating and computing mechanisms returned to the zero position. As heretofore stated, the return of 110 the machine is effected by the coil spring 71 in the roller 68, and occurs when the thumb-plate 46 (Figures 13 and 15) is pushed inward, which operates, through the mechanism heretofore described, to draw inward 115 the slide plate 38 and to move the clutch member 33 from engagement with the gear 29. This operation disconnects the measuring roller from the chain of gearing, which is directly responsive to the power exerted 120 through shaft 69 and coil spring 71, and 125 through shaft 69 and coil spring 71, and 130

the parts are thereby restored to the zero position. The mechanism now brought into play may be described as resilient stop mechanism, and is designed to arrest the return movement of the parts when the hands and charts reach the zero position without shock to the mechanism. This mechanism has been described above, and comprises, essentially, the dog 197 with its spring 198, and the dog 200 with its spring 201, so that it is only necessary to recite the operation involved. In the return movement, the pin 194 first strikes the end of dog 197 and moves it to the position shown in Figure 13 against the resistance of spring 198. This tends to retard the movement of disk 192, and also by turning plate 199 to move the free end of dog 200 into the path of the shoulder 193 on said disk, which shoulder then engages said dog and moves it inward against the resistance of spring 201, or to the position shown in Figure 13. The additional resistance offered by spring 201 is sufficient to arrest the movement of the parts at substantially the zero position. There is usually a slight movement beyond this position, as the action of the springs is, of course, not positive; but this is corrected by the spring 201 returning the dog 200 into engagement 30 with pin 200^a, which slight movement brings the parts to rest at the zero position.

I also arrange for operating a brake to prevent the accidental movement of the measuring roller after the presser roller has 35 been raised to insure that only the actual amount of goods measured shall be computed.

Referring particularly to Figure 17, the numeral 208 indicates a slide plate which 40 is mounted by means of slots at either end on screws 209, and has projecting from its upper side a tongue 210 which is in the path of the lower end of the lever 175. Pivots mounted intermediate its ends on the slide plate 208, at 211, is a dog 212 the upper end of which is connected to one end of a coil spring 213 the other end of which is connected to a pin 214 on the frame plate 23. This spring normally holds the upper end 45 of the dog in engagement with a stop pin 213^a. Mounted on the spindle 25 of the measuring roller on the outer side of the cam disk 26 is a brake disk 215 (Figure 18) which has a knurled periphery. The lower, 50 or free end of the dog 212 is provided on its inner side with a serrated face, as indicated at 216. When the presser roller 22 is raised the lever 175 in its movement will 55 strike the tongue 210 on the slide plate 208 and move said slide plate with the dog 212 toward the left, as viewed in Figure 17. This movement of the slide plate 208 will 60 place the spring 213 under tension, and will bring the lower serrated end of the dog 212 65 into engagement with the corresponding

knurled surface of the brake disk 215, forcing the upper part of the dog out of contact with stop-pin 213^a, the lower end of which is thus held in yielding engagement with the brake disk, and thereby prevents movement in either direction of the measuring roller 21. When the presser roller is again lowered by pressing in the release button 188, the spring 213 operates to return the slide-plate 208 to its former position and thus carry the serrated end of the dog out of contact with the periphery of the brake disk. 70

One of the important features of the invention consist in decreasing the height of the machine over what formerly obtained in the commercial machine of this type. Such reduction in height is secured by so disposing the operative parts that the dial and chart, at opposite ends of the machine, respectively, are on a level with each other and with the upper elevation of the ribbon base, i. e. of the cover plate 160, as will appear from an inspection of Figure 1 in connection with Figures 11 and 15. 75

I claim:

1. A ribbon measuring and cost computing machine, comprising, in combination, a base, length indicating and cost computing devices mounted in the base near opposite ends of the base and on a level with each other and with the upper elevation of said base, a measuring roller operatively connected with said devices, and mounted on the base between the length indicating and cost computing devices and adapted to be rotated by the ribbon being measured to operate said mechanisms, and a winding drum also mounted on said base and substantially parallel with said measuring roller for winding up the ribbon and thereby drawing it over the measuring roller. 85

2. A ribbon measuring and cost computing machine comprising, in combination, a base, length indicating and cost computing devices mounted therein, a slotted cover plate extending over said cost computing device and permitting view thereof, a measuring roller operatively connected with said devices, and adapted to be rotated by the ribbon being measured to operate the said mechanisms, said measuring roller projecting part way through the slot in said cover plate, a pressure roller located over said measuring roller for pressing the ribbon into frictional engagement with said measuring roller, and located above said cover plate, a plurality of means for moving said presser roller toward and from the measuring roller, and a case extending over said rollers parallel with and at a distance from said cover plate and having a clear glass window permitting view of the rollers beneath it. 110

3. In a ribbon measuring machine, in combination with a base, length indicating mech- 120

- anism mounted therein, a measuring roller operatively connected with said mechanism, and adapted to be rotated by the ribbon being measured to operate said mechanism, a 5 presser roller for pressing the ribbon into frictional engagement with the measuring roller, and movable toward and from the same, a plurality of means for operating the presser roller, a support on said base over 10 which said ribbon passes as it is measured, a gripping device movable into engagement with said support to hold the ribbon so that it may be severed at the end of a measured portion, and mechanism under the control 15 of the operator for simultaneously raising said presser roller and lowering said gripping device.
4. In a ribbon measuring machine, in combination with a base, length indicating mechanism mounted therein, a measuring roller operatively connected with said mechanism, and adapted to be rotated by the ribbon being measured to operate said mechanism, a presser roller for pressing the ribbon into 20 frictional engagement with the measuring roller and movable toward and from the same, a plurality of means for operating the presser roller, a slotted runway provided on the base, a knife slidably mounted therein 25 and movable thereover for severing the ribbon at the termination of a measured portion, a gripping device movable into engagement with said runway to hold the ribbon while it is being severed, and mechanism 30 under the control of the operator for simultaneously raising said presser roller and lowering said gripping device.
5. In a ribbon measuring machine, in combination with a base, length indicating mechanism mounted therein, a measuring roller operatively associated with said mechanism, and adapted to be rotated by the ribbon being measured to operate said mechanism, a presser roller for pressing the ribbon into 35 frictional engagement with the measuring roller, and movable toward and from the same, a plurality of means for operating the presser roller, a slotted runway provided on the base, a knife slidably mounted therein 40 and movable thereover for severing the ribbon at the termination of a measured portion, a gripping device movable into engagement with said runway to hold the ribbon while it is being measured, a rock shaft, a 45 push bar for rocking the same, and means operatively connecting said rock shaft with said presser roller and said gripping device, respectively, whereby, by rocking said shaft, to simultaneously raise the presser roller and 50 lower said gripping device.
6. In a machine of the class described, in combination with a base affording a ribbon support, length indicating mechanism mounted therein, a measuring roller operatively associated with said mechanism, and 55 adapted to be rotated by the ribbon being measured to operate said mechanism, means for drawing the ribbon over said measuring roller and said support to grip the ribbon and hold it while it is being severed, said gripping device comprising a pair of independently movable members.
7. In a ribbon measuring machine, in combination with a base affording a ribbon support, length indicating mechanism mounted in said base, a measuring roller operatively associated with said mechanism, and adapted to be rotated by the ribbon being measured 60 to operate said mechanism, means for drawing the ribbon over said measuring roller and said support, a rock shaft, a pair of gripping members pivotally mounted on the base above said support, independent connections between said rock shaft and each of said members, and means for rocking said shaft to move said members into engagement with the ribbon on said support to hold the ribbon while it is being severed at the end 65 of the measured portion.
8. In a ribbon measuring machine, in combination with a base affording a ribbon support, length indicating mechanism mounted in said base, a measuring roller operatively associated with said mechanism, and adapted to be rotated by the ribbon being measured 70 to operate said mechanism, means for drawing the ribbon over said roller and said support, a pair of gripping members pivotally mounted on the base above said support and capable of independent movement, a rock shaft, means independently connecting each of said members with said rock shaft, and means for rocking said shaft to move said 75 members into engagement with the ribbon on said support to hold it while it is being severed, the construction permitting either of said members to move independently of the other to compensate for differences in 80 the thickness of the ribbon being gripped.
9. In a ribbon measuring machine, in combination with a base affording a ribbon support, length indicating mechanism mounted in said base, a measuring roller operatively associated with said mechanism, and adapted to be rotated by the ribbon being measured 85 to operate said mechanism, means for drawing said ribbon over said roller and said support, a pair of arms pivotally mounted 90 at one end to extend over said support, a finger pivotally mounted intermediate its ends on the other end of each arm, springs normally holding the outer end of said fingers in an elevated position, a rock shaft having 95 cranks, pins projecting from said arms and said cranks, springs connecting a pin on each arm with a pin on a corresponding crank, links having slotted connections at 100 their opposite ends with the corresponding 105

- pins of said cranks and arms, and means for rocking said rock shaft to move said members into engagement with the ribbon on said support to hold it while it is being severed
- 5 at the end of a measured portion, the construction permitting either of said arms to be moved independently of the other to compensate for differences in the thickness of the ribbon being gripped.
- 10 10. In a ribbon measuring machine, in combination with a base affording a ribbon support, length indicating mechanism mounted in said base, a measuring roller operatively associated with said mechanism, and
- 15 adapted to be rotated by the ribbon being measured to operate said mechanism, means for drawing said ribbon over said roller and said support, a pair of arms pivotally mounted at one end to extend over said support, a
- 20 finger pivotally mounted intermediate its ends on the other end of each arm, springs normally holding the outer ends of said fingers in an elevated position, a rock shaft having cranks, pins projecting from said
- 25 arms and said cranks, springs connecting a pin on each arm with a pin on a corresponding crank, links having slotted connections at their opposite ends with the corresponding pins of said cranks and arms, and means
- 30 for rocking said shaft to draw the arms toward said support, the rear ends of said fingers being adapted to engage the support to turn the fingers on their pivots to cause their outer ends to move toward the support
- 35 in such movement of the arms, and the construction permitting either of said arms to be moved independently of the other to compensate differences in the thickness of the ribbon being gripped.
- 40 11. In a ribbon measuring machine of the class described, a winding drum for winding up the ribbon being measured, said winding drum comprising a head having a tapered outer end and flexible fingers secured at their
- 45 inner ends to said head and projecting beyond the same in spaced relation thereto.
12. In a machine of the class described, a base having a head provided with a circular recess, a winding drum for winding the ribbon being measured, said winding drum having its inner end housed in said recess and its outer end free, and means for rotating said winding drum.
- 50 13. In a machine of the class described, in combination with a base having a head providing a housing and a circular recess, a bearing inclosed in said housing and having a spindle, a winding drum mounted on said spindle and having its inner end working in said circular recess, and a crank for turning said winding drum.
- 55 14. In a ribbon measuring machine having a base provided with a slotted runway over which the ribbon measured is adapted
- 60 to pass, a cutter slidably mounted in said
- runway and movable thereover, a pivoted member housed in a recess in the frame of the machine and having a spring-controlled reel rotatably mounted at its free end, a wire wound on said reel and connected to said cutter, said pivoted member being capable of being turned on its pivot to carry the reel out of said recess and render it accessible to the operator, and means for normally retaining said pivoted member in position in said recess.
- 65 15. In a ribbon measuring machine having a base provided with a slotted runway over which the ribbon measured is adapted to pass, a cutter slidably mounted in said runway and movable thereover, a pivotally mounted member housed in said frame, a spring-controlled reel rotatably mounted on the free end of said member, a cable wound on said reel and connected to said cutter, a pivotally mounted plate normally closing the housing of said member and reel, and a link connected with said plate and pivoted member whereby, when the plate is turned on its pivot, said member will be drawn outward from its housing to move the reel into a position accessible to the operator.
- 70 16. In a ribbon measuring machine having a base provided with a slotted runway over which the ribbon measured is adapted to pass, a cutter slidably mounted in said runway and movable thereover, said runway being provided with longitudinal recesses on opposite sides of said slot, a pair of hold-down fingers mounted above said runway and movable to cause their lower edges to enter said recesses, and means for operating said hold-down fingers.
- 75 17. In a ribbon measuring machine having a base provided with a slotted runway over which the ribbon measured is adapted to pass, a cutter slidably mounted in said runway and movable thereover, a pair of longitudinal recesses provided in the upper side of said runway on the opposite sides of its slot, pads mounted in said recesses with their upper surfaces below the tops thereof, a pair of hold-down fingers mounted to extend over said recesses and movable to cause their lower edges to enter the same, and means for operating said hold-down fingers.
- 80 18. In a ribbon measuring machine, a measure indicator, a measuring roller adapted to be rotated by the ribbon to be measured, gearing operatively connecting said measuring roller and measure indicator, a knurled brake disk connected to said measuring roller, a presser roller, means for moving said presser roller into and out of engagement with the measuring roller, a brake having a serrated portion, and means for automatically moving the serrated portion of said brake into engagement with said brake disk to lock the measuring roller
- 85 90 95 100 105 110 115 120 125 130

against movement when the presser roller is moved out of engagement with said measuring roller.

19. In a ribbon measuring machine, in combination with a measure indicator, a measuring roller adapted to be rotated by the ribbon being measured, gearing operatively connecting said measuring roller and said measure indicator, a brake disk connected with said measuring roller, a pivotally mounted presser roller, lever mechanism operable at will to move said presser roller out of engagement with said measuring roller, means for moving the presser roller into engagement with the measuring roller, a slide bar, and a spring-controlled brake mounted on said slide bar, one member of said lever mechanism being adapted to engage such slide bar to carry said brake into engagement with the brake disk when the presser roller is moved out of engagement with the measuring roller.

20. In a ribbon measuring machine, in combination with an extended base, length indicating mechanism mounted in said base, a measuring roller adapted to be rotated by the ribbon being measured to thereby operate said mechanism, and a winding drum extending parallel with the extended base and rotatably mounted at one end for winding the ribbon being measured and thereby drawing it over said measuring roller, said measuring roller being inclined to the longitudinal axis of said base, whereby to direct

the course of the ribbon toward the mounted end of the winding drum as it is being wound.

21. In a ribbon measuring machine, in combination with a measure indicator, a measuring roller adapted to be rotated by the ribbon being wound, gearing operatively connecting said measuring roller with said measure indicator whereby the latter is operated from the measuring roller, means for automatically returning the parts to zero after a measuring operation, and means for resiliently arresting the parts at the zero position comprising a cam disk rotatable with said gearing and having a pin and a shoulder, a pivotally mounted member carrying a spring-controlled dog for engaging said pin, and a pivoted spring-controlled dog for engaging said shoulder, whereby, in the measuring operation, said spring-controlled member will be released by the movement of the pin away from said dog to carry the pivoted dog out of the path of said shoulder and, on the return of the parts to zero, said pin will engage said dog and cause said pivoted member to carry the pivoted dog into the path of said shoulder, whereby said pivoted dog will yield against the tension of its spring, and a stop against which said pivoted dog is normally drawn by its spring.

In testimony whereof, I have hereunto set my hand.

DOUGLAS TURNER.
